GEORGE E. PICKUP, OF NEWARK, OHIO, ASSIGNOR TO THE WEHRLE COMPANY, OF NEWARK, OHIO, A CORPORATION OF OHIO

DRAWER CONSTRUCTION FOR STOVES AND THE LIKE

Application filed October 4, 1928. Serial No. 310,277.

This invention relates to improvements in utility drawers for stoves and more particularly to the construction of a drawer disposed beneath the burners in gas or other types of cooking ranges.

One object is to provide a new and improved drawer of the above character having an auxiliary receptacle which can be opened conveniently without withdrawing said drawer so as to render readily accessible certain frequently used utensils such as condiment containers and the like.

Another object is to provide a drawer for cooking stoves and the like having a front wall of novel construction and artistic appearance with a movable panel which constitutes a closure for an auxiliary compartment normally disposed within the drawer proper.

Other objects and advantages of the invention will become apparent from the following detailed description taken in connection with the accompanying drawings, in which

Figure 1 is a fragmentary perspective view of a gas range equipped with a drawer embodying the features of the present invention.

Fig. 2 is a vertical sectional view through that portion of the range shown in Fig. 1.

Fig. 3 is a view similar to Fig. 2 with the drawer partially withdrawn.

Fig. 4 is a fragmentary perspective view of the range with the drawer removed.

Fig. 5 is a perspective view of the drawer.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the drawings the invention is illustrated in a gas range construction having the usual base frame 6 mounted on legs 7 and supporting at one end an oven structure 8 whose front surface may be completely enameled and

which projects downwardly over a portion of the base frame so as to conceal the same. Mounted above the opposite end of the base frame is a framework 9 in which the open burners of the range are disposed.

Beneath the burners and adjacent the oven structure is a horizontal and forwardly opening compartment in which the improved drawer is mounted. This compartment is defined by the said wall 10 of the oven, side, rear and bottom walls 11, 12 and 13 secured to the base frame 6, and a top wall formed by the removable drip pan 14 which is disposed beneath the burners.

In the present instance the drawer is formed of sheet metal with side walls 15, a bottom wall 16, a rear wall 17, and a front wall 18. Horizontal ledges 19 overlie the sides of the drawer and are secured to the side walls of the drawer compartment. The front wall 18 is substantially larger in area than the cross section of the drawer, the upper edge extending above and concealing the drip pan 14. The lower edge projects beyond the bottom of the drawer so as to form a flange 20 which overlaps the base frame 6 and terminates substantially at the same level as the lower edge of the front surface of the oven structure. Thus, the normally exposed portion of the base frame shown in Fig. 4 is completely concealed when the drawer is in closed position. The surface of the front wall can be readily enameled and, therefore, conforms to the oven front giving the stove front as a whole a balanced and artistic appearance.

Disposed within the drawer is an auxiliary receptacle mounted for bodily movement outwardly through a rectangular opening 21 in the front wall of the drawer so as to be accessible without necessitating withdrawal of the drawer. This compartment is defined in part by a substantially flat closure plate 22 conforming to the shape of but substantially larger than the opening 21 and having a convex outer surface, the curved peripheral edge of which abuts against the front wall 18 of the drawer so as to constitute the plate a beveled panel for the wall. In the present instance the plate 22 is disposed externally

of the drawer being hinged at 23 to the plate 22 at the lower edge of the opening 21. A handle 24, secured to the plate 22, constitutes a common means by which the drawer or the 5 auxiliary receptacle can be opened selectively.

Secured to the rear side of the closure plate 22 is a sheet metal member 25 defining the rear side and bottom walls of the auxiliary receptacle, the front wall being formed by 10 the closure plate. The vertical and lateral dimensions of the member 25 are smaller than those of the opening 21 which permits the receptacle to be tipped forwardly through the opening from its normally concealed position, as shown in Fig. 2, into the 15 open position shown in Fig. 3. If desired, the auxiliary receptacle may be partitioned as shown in Fig. 5 so that the utensils, such as small condiment cans, will be maintained in 20 upright position. Preferably, the rear wall of the auxiliary receptacle has a projection 26 against which the rear surface of the plate 18 acts as a stop to limit the forward tipping movement of the receptacle to the position 25 shown in Fig. 3, in which position the receptacle is maintained by the weight of its contents which acts forwardly of the hinge axis. When the receptacle is positioned as in Fig. 2 its weight acts rearwardly of the hinge 30 axis, thereby maintaining the receptacle closed.

When it is desired to open the auxiliary receptacle downward pressure is applied to the handle 24 which tips the plate 22 forwardly into the position shown in Fig. 3. To withdraw the slidable drawer without opening the auxiliary receptacle an upward force is applied to the handle at the same time as the drawer is slid forwardly.

10 I claim as my invention:

1. In a cooking range providing a horizontal forwardly opening compartment, the combination of a drawer slidably mounted in said compartment and withdrawable therefrom, said drawer having a front wall with an opening therein, and a member for closing said opening hinged to said wall and swingable forwardly therefrom to afford access to the interior of the drawer while the 50 drawer is in closed position.

2. In a cooking range providing a horizontal forwardly opening compartment, the combination of a drawer slidably mounted in said compartment and withdrawable therefrom said drawer having a front wall with an opening therein, a receptacle for closing said opening hinged at its lower edge to said wall and swingable forwardly therefrom to afford access to the interior of the drawer while the 55 drawer is in closed position, and a common actuating handle by which said drawer may be opened or said receptacle opened while said drawer is closed, said handle being secured to said receptacle.

3. In a cooking range providing a hori-

zontal forwardly opening compartment, the combination of a drawer slidably mounted in said compartment and withdrawable therefrom, said drawer having a front wall with an opening therein, a member for closing said opening hinged at its lower edge to said wall, and means carried by said member and providing a receptacle which is disposed within said drawer when said member is in closed position and which opens externally of the 70 drawer when said member is in open position.

4. In a cooking range having a plurality of open top burners, side, back and bottom walls forming a forwardly opening compartment beneath said burners, a drawer in said compartment slidable forwardly out of said compartment and a drip pan removably mounted within said compartment so as to form a top wall therefor, said drawer having a forward wall serving to close the forward side of the compartment and conceal said drip pan when the drawer is closed.

5. In a cooking range providing a horizontal forwardly opening compartment, the combination of a drawer slidably mounted in said compartment and withdrawable therefrom, said drawer having a front wall with an opening therein, an upwardly opening receptacle pivoted on said front wall and movable from a position within said drawer to a position outside of said drawer, said receptacle being accessible through the top of said drawer when said drawer is in its open position.

In testimony whereof, I have hereunto affixed my signature.

GEORGE E. PICKUP.
